ACTION FOR UPRIGHT PIANOS

Ralph A. Wolfe, Wichita, Kans.

Application April 25, 1952, Serial No. 284,287

5 Claims. (Cl. 84—240)

1

This invention relates to an improved and highly simplified action for upright pianos.

It is the chief object of the invention to provide an action by which motion is transmitted from the key arm to the hammer and to the damper in a much simpler manner, and in which a considerable number of the parts used in conventional actions are completely eliminated.

It is a further object to provide an action in which the key motion is transmitted to both hammer and damper in a more direct and positive manner than in conventional actions, and in which the required adjustments are fewer than in conventional actions.

More specifically the invention omits the action brackets, the jack regulating bar, the jack and jack spring, the bridle strap or tape, the check, the backstop, the prolong and prolong lever, and the hammer rail, all of which are present in conventional actions. As a result, my invention provides a much less expensive construction, and one having a longer trouble free life. From a purely economic standpoint a high quality piano embodying my improved action is being sold at a retail price approximately equivalent to the wholesale price of the least expensive piano now on the open market.

Another object is to provide an action which requires less vertical space, less space in fore and aft depth, and less lateral space than other actions. Hammer blow adjustment for various key motions is simple and direct. The elimination of the bridle tape alone makes for greater dependability.

A further object is to provide an action which is so constructed that a hammer cannot be blocked against a string, nor can a hammer vibrate fore and aft to strike a string several times.

The invention will be more clearly understood when the following description is read in connection with the accompanying drawings, in which:

Fig. 1 is a side elevation, with parts in section, showing my simplified action with key, hammer and damper in idle or at rest positions;

Fig. 2 is a similar view showing the key fully depressed, damper retracted, and hammer traveling toward the string; and

Fig. 3 is a similar view showing the hammer actually contacting the string and about to return to its Fig. 2 position, the key still being in a fully depressed position.

In the drawings the action supporting frame as a whole includes an upright damper rail 10,

2

a horizontal key bed 11, an action rail 12, and a balance rail 13, all of which extend the full width of the piano key board, and serve to mount the actions for the individual strings.

5 A wippen 14 is pivoted at 15 on a trunnion cradle 16, fixed on the action rail. The forward end of the wippen is fitted with a stop screw 17, the head of which contacts felt pad 18 to adjustably limit wippen movement. It also carries an upright damper spoon 19. A hammer butt 20 is pivotally mounted at 21 in a trunnion cradle 22, and seats on the aft end of the wippen 14. The butt supports the usual hammer shank 23 and hammer 24. A curved leaf spring 25 has one end mounted on the trunnion cradle, and its other end bears against the forward edge of the butt 20 to normally keep the butt seated flat against the upper surface of the wippen, as shown in Figs. 1 and 2.

10 The wippen is supported in the at rest position shown in Fig. 1 by an adjustable capstan 26 mounted on the forward end of a conventional key arm 27, the head of the capstan bearing against a felt pad 28 carried by the wippen.

15 20 25 The key arm is fulcrumed on the balance rail 13 and is conventionally guided in its movement by upright pins 29 and 30 cooperating with fore and aft slots 31 and 32 in the key arm. The forward end of key arm 27 normally rests on a felt pad 33, while its rear end contacts pad 34, when depressed.

20 25 30 35 The upright damper lever 35 is pivoted at 36 in a trunnion cradle 37 fixed on the damper rail 10. The lower end of damper lever 35 is spring pressed by leaf spring 38 into contact with the upper end of spoon 19, a pad 39 absorbing the actual contact. A resilient wire 40 is carried by lever 35, and in turn adjustably supports damper block 41, the vertical adjustment being accomplished by a set screw 42. The forward end of block 41 carries a damper 43 which normally rests against string 44 as a result of the pressure of spring 38 against the lower end of the damper lever.

Operation

35 40 45 The three drawing views clearly illustrate the operation of the described action. When key arm 27 is depressed to the Fig. 2 position, capstan 26 forces wippen 14 to pivot upward until stop screw 17 stops further movement. Simultaneously spoon 19 contacts and forces damper lever 35 to pivot against the action of spring 38, moving damper 43 to the position shown, out of contact with string 44.

During the described movement of the wippen, hammer 24 is moved rapidly toward string 44. When wippen movement is abruptly stopped, kinetic energy causes hammer 24 to continue its forward movement until it strikes string 44 (as in Fig. 3), the hammer butt 20 pivoting about point 21 against the action of spring 25 to permit such hammer movement. The hammer blow is smart and the hammer is immediately returned to its Fig. 2 position both due to rebound from the string and to the action of spring 25. Spring 25 immediately seats the hammer butt against the wippen, as in Fig. 2, and prevents further string contact by the hammer, even though the key arm may remain fully depressed.

From the above description it will be observed that this invention provides a more direct cooperation of the various parts of the action, that the number of parts required has been reduced to a minimum, and that required adjustments are simple and few. It makes possible the manufacture of a piano which is relatively small in size, yet high in quality at a much lower cost than pianos having conventional actions. It also provides for a longer trouble free life due to its simplified construction.

Having described the invention with sufficient clarity to enable those familiar with this art to construct and use it, I claim:

1. A piano action comprising: a fixed frame; an upright damper carrying lever pivotally mounted intermediate its ends on said frame; spring means urging said lever to a normal position in which the damper is in contact with its string; a wippen pivotally mounted intermediate its ends on said frame, the inner end of said wippen being positioned adjacent an end of the damper carrying lever; a spoon carried by said inner end of the wippen for contacting and pivoting the damper carrying lever in a direction to move the damper out of contact with its string when the wippen is pivoted away from its normal position; a hammer supporting butt normally seated on the outer end of said wippen and pivotally secured thereto to afford movement of the hammer toward said string; resilient means normally maintaining the butt in its seated position; a key arm rockably supported intermediate its ends on said frame, the inner end of the arm positioned to directly contact and move the outer end of said wippen when the opposite end of the key arm is depressed; and adjustable means for stopping the pivotal movement of the wippen before the hammer is moved bodily by the wippen into actual string contact.

2. A piano action comprising: a frame; an upright lever carrying a string contacting damper on its upper end, said lever being pivotally mounted intermediate its ends on said frame; a key arm rockably supported intermediate its ends on said frame, the inner end of said key arm being positioned adjacent the lower end of said lever; a wippen pivotally mounted intermediate its ends on said frame between the adjacent ends of the lever and key arm; a lever contacting spoon on the inner end of the wippen; a wippen contacting capstan on the inner end of the key arm; a hammer supporting butt normally seated on the outer end of the wippen and pivotally secured thereto to afford movement of the hammer toward its string; resilient means normally maintaining the butt in its seated position; resilient means nor-

5 mally maintaining the lever in a position in which its damper is in contact with the string and its lower end is in contact with said spoon; and means for stopping wippen movement prior to 10 actual contact of the wippen supported hammer with said string, whereby motion is transmitted directly from the key arm to the wippen and simultaneously from the wippen directly to the damper lever, the wippen simultaneously moving the hammer toward its string; kinetic energy causing the hammer to continue its stringward movement after the wippen has ceased moving.

3. A piano action comprising: a frame; a damper lever, a wippen, and a key arm, each pivotally supported intermediate its ends on said frame, one end of the key arm being positioned to contact one end of the wippen and pivot it when the opposite end of the key arm is depressed; a spoon carried rigidly by the opposite end of the wippen for directly contacting one end of the damper lever to pivot said lever when the wippen is pivoted; a damper carried by the opposite end of the damper lever, and normally in contact with its piano string; a string striking hammer having one end pivotally supported on the wippen in a position normally spaced from said string, said hammer adapted to be moved bodily toward said string when the wippen is pivoted, and to move pivotally into contact with said string after wippen movement ceases; resilient means normally restraining the hammer from pivotal movement with relation to the wippen; and means for stopping the pivotal movement of the wippen before the hammer is carried bodily to a position of string contact.

4. A piano action comprising: a substantially horizontally positioned wippen pivoted intermediate its ends for movement in a vertical plane; an upright hammer pivoted on the outer end of said wippen for movement toward a string in the same vertical plane; means limiting the pivotal movement of said hammer in a direction away from said string; spring means resisting the pivotal movement of said hammer in a direction toward said string; an upright damper lever pivoted intermediate its ends for movement in the said plane toward and away from said string; a damper carried by the upper end of said lever; spring means urging said lever to pivot in a direction to normally maintain said damper in contact with said string; a spoon carried on the inner end of said wippen in contact with the lower end of said damper lever for retracting the damper from string contact when the wippen is pivoted in a direction to move the hammer toward the string; a key arm pivoted intermediate its ends for movement in the same said vertical plane, the inner end of the key arm being in contact with the outer end of the wippen for pivoting the wippen in a direction to move the hammer toward said string when the outer end of the key arm is depressed; and means for stopping the pivotal movement of the wippen in the mentioned direction before the wippen has moved the hammer bodily into contact with said string.

5. The action described in claim 4 and a capstan carried on the inner end of said key arm for making adjustable contact with the outer end of said wippen.
